UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A LAMP STANDARD.

Application filed July 22, 1922. Serial No. 3,173. Term of patent 14 years.

To all whom it may concern:

Be it known that I, JOSEPH W. GOSLING, a citizen of the United States, residing in Schenectady, county of Schenectady, State of New York, have invented a new, original, and ornamental Design for Ornamental Lamp Standards, of which the following is a specification.

The accompanying drawing is a view in elevation of my ornamental lamp standard.

I claim:

The ornamental design for a lamp standard as shown.

In witness whereof, I have hereunto set my hand.

JOSEPH W. GOSLING.
